UNITED STATES PATENT OFFICE.

JOHN LUCAS, OF STOCKTON, CALIFORNIA.

GRAIN AND SEED SEPARATOR AND CLEANER.

1,310,759.

Specification of Letters Patent. Patented July 22, 1919.

Application filed May 23, 1912. Serial No. 699,182.

To all whom it may concern:

Be it known that I, JOHN LUCAS, a citizen of the United States, residing at Stockton, San Joaquin county, California, have invented certain Improvements in Grain and Seed Separators and Cleaners, of which the following is a specification.

This invention relates to grain and seed separating and cleaning machines, and is for the purpose of recleaning and separating different kinds of grains and seeds in a better and more practical manner, and consists of the construction, combination and arrangement of all its parts, and construction of its auxiliary parts, any one of which, if incorporated would be beneficial to other machines of the same class, and therefore the invention is the combination of all its parts, and the construction of its auxiliary or special parts, as hereinafter shown and described, and specifically pointed out in the specification and claims.

In the drawings forming parts of the specification the principal features, are the supplying the grain to the force feed, the manner of taking care of the surplus, the under force feed, the adjustment and relief of the feed, the arrangement of the sieves, the construction and means for regulating the under screens, the adjustable detachable catch board, between the screens, and the arrangement of the lower hopper or receptacle of 34—34 to catch or gather the screenings, with a suspended conveyer through the same, to facilitate the adjusting of the catch board.

Figure 1, consists of a cross section through an auger conveyer, and under force feed, and means to regulate, and relieve the feed.

Figs. 1—2 and 6, show the entire combination, construction and relative position to each other of the several auxiliary or different parts that are necessary to the requirements of the separator and cleaner.

Fig. 3. is a perspective view of the detachable catch board. Fig. 4. is a perspective detail view of Fig. 1.

Fig. 5. is a perspective detail view of the under force feed.

Fig. 6. sheet 2 is a detail front elevation of the cleaner showing auger conveyer 1—33—37 as well as relief spout 38 for the purpose hereinafter described.

In the drawing Fig. 6 shows the receiving hopper 43., elevator 44. conveyer 1. relief spout 38. return auger 33 and secondary hopper 40 relating to the supplying of the grain to the force feed, and the taking care of the surplus grain. Figs. 1. 4. and 5. relate to my under force feed, the distinguishing features of which are that it will distribute and feed more or less as required, and in case of a choke up it can be relieved and readjusted almost instantly while in motion.

The grain to be cleaned and separated is placed in hopper 43. Fig. 6. It enters elevator at 42. and it is then elevated by elevator 44 to auger conveyer 1. that conveys to and distributes the grain through the full length of the opening 2. in bottom of conveyer box 1. It is then in receptacle 4. or as much as receptacle 4 will retain. If there is a surplus it is carried on to and falls down relief spout 38. to conveyer 33. which carries it to secondary hopper 40. and reenters elevator at 41 preceding the grain in the receiving hopper 43. This system gives a steady and full supply to the feed, as well as serving to obviate blocking or running over. The grain conveyer 33, also returns unfinished grain to be worked over as the whole has the function of a retaining, and a mixing machine thereby equalizing uneven mixtures of grain and meeting the requirements of the machine as a separator. The machine can be well supplied with grain and deliver finished products, slow or fast, as the occasion may require thereby delivering a uniform grade of its products in a higher or lower state of perfection as required. The grain can pass around and through the machine any number of times.

Receptacle 4. is composed of board 5 back board 6 at bottom, and the concave corner piece 7. The outer ends of board 6, are inclosed with sheet iron, that slide inside of wooden walls shown in Fig. 4. Receptacle 4. is sustained by its hinges 8.—9. shown in Fig. 5. which are attached to, and swing under conveyer box 1, and are held in position by flat springs 10 and 11 shown in Fig. 1, Fig. 4, and Fig. 5. Board 12 shown in Fig. 1. and Fig. 4. is full length of the under force feed, and it is supported at its ends by the walls of the cleaner and is for the purpose of keeping the grain from pass-

ing out over the feed. Under force feed 13, shown in Figs. 1, 4, 5, and 6., is a spurred shaft, and it is supported, by walls of cleaner, shown in Fig. 6. It is rotated on its 5 axis by a belt so that it drags the grain out at 14. Fig. 1. Levers 15—16, are attached one at each end of board 5, and the outer ends are made fast to slat 17, at 18—19 as shown in Fig. 4. Slat 23, is stationary and 10 it is made fast to walls of the cleaner shown in Fig. 6. Hand screws 20—21, pass through threaded burrs or nuts attached to slat 23, and come in contact with slat 17, thereby holding against springs 10—11, as shown in 15 Figs. 4 and 5. To increase the feed I enlarge the opening at 14, by turning down screws 20—21 until feed is gaged as required. In case of a choke up slat 17, may be pulled down making the opening at 14 20 larger, and when released it springs back to the gage set by hand screws 20—21.

In the drawings, after the grain is forced out at 14, it falls onto sieves 24—25, which 25 form a hurdle. Sieves 26—27—28 are a hurdle and are set at an adjustable inclination and they are held in position in an appropriate shaking shoe. The light coarse objectionable matter passes over across the 30 top of these sieves, and the heavier and smoother grain passes through. The upper cross bar or slat, of sieve 24, is made narrow, and under it in sieve 25 the slat is wide, hence the grain passing through sieve 24, the lighter and rougher is slower, the 35 heavy and smoother seeks the bottom and accumulates on the wide slat, before passing on to the sieve 25 thereby facilitating the better flooding and separating of the grain, on the sieve 25. In the sieves 26, 27, and 28, 40 the slats are alternately narrow and wide as shown. In Fig. 2, 1^a, shows the edge of the deck or covering to the cleaner. 2^a, is a roller curtain fixture that takes up the curtain, 3^a, provided with a slat at bottom, and 45 with the side walls shown in Fig. 6 sheet 2, forms a hood over the sieves 24, 25, 26, 27, and 28. The wind or air current from the fan passes out on a direct line from the fan to and below the curtain thereby preventing 50 the air current from interfering with the grain on the upper portion of the sieves or hurdles, as well as causing the air to be compressed in the hood, and thus have a bearing down effect on the grain, thereby 55 holding it down flat on the sieves. When necessary the curtain may be raised to admit of the air current passing through higher up on the sieves.

In my invention I have a new construction 60 of a hurdle of screens, comprising a series of superimposed inclined parallel shaking screens each screen being supported at its ends by imperforate shelf members, the shelves at the upper ends of the screens alternating in width from narrow to broad 65

downward through the series, (when possible) and the grain passing downward through the upper ends of the screens finds little lodgment on the narrow shelves, and causes less flooding, and it has more agitation, although it does lodge and gathers depth on the broad shelves when passing over them to the alternate screen, thereby producing more capacity and a better flooding of the alternate screens. The narrow 70 shelves are for the purpose of supporting the wire netting only.

A new construction for under screening. This construction provides a wider range 75 for grading and fine screening of the grain, after it has passed through coarser sieves above to fine screens 29—30, detachable catch board 31, hopper or gatherer 34—34, and auger conveyers 32—33 and 37., as shown in Figs. 2 and 6., although it forms 80 and is the lower part of my improved separator and cleaner. I wish to claim it broadly as such it is thought would be an improvement in any cleaner of its class.

Fine screens 29—30, and detachable catch 90 board 31, are held in slides or grooves, of an appropriate shaking shoe, and each is adjustable, and may be moved toward or from conveyer 32, or either can be removed as required obtaining thereby different results. 95 Thus if fine screen 29, and catch board 31, (as shown in Fig. 2) are moved in their grooves toward conveyer 32., they would catch less of and a cleaner grain from sieves 26—27—28 where they are better flooded. 100 The grain from said sieves is then carried over screen 29, and delivered finished at 32., and catch board 31, makes it possible and does carry the screenings from screen 29, over conveyer 33, and delivers them in 105 screenings hopper 34, at 35., thereby preventing if so desired the screenings from screen 29, from mingling with seconds on screen 30. Fine screen 30 would then catch more seconds or middlings to be returned by 110 conveyer, 33, to be worked over. If screen 30 were moved in its grooves toward conveyer 33, it would catch less seconds putting more or all of them if desired into screening hopper 34, at 36. The seconds caught 115 from lower end of sieve 28, are delivered by screen 30, to conveyer 33 and are carried back to the elevator to be worked over. Screenings from screen 30, drop into hopper 34, at 36, thereby with the use of the catch 120 board 31 between the screen 29 and 30, it is possible to divide the grain to be screened, each division passing over the separate screens, the board 31 keeping the screenings that pass through screen 29, from reentering, 125 or falling on to grain that is on screen 30., thereby nearly doubling the screening capacity of the under shoe, which works well in grading barley.

If the greater part of the barley or other 130

grain is to be saved, and a more thorough screening is required, let fine screens 29,--30., and catch board 31, remain as shown in Fig. 2, but remove catch board 31, and the screenings from screen 29., fall on screen 30, and are rescreened by screen 30., thereby reducing screenings to a minimum.

Auger conveyer 33, suspended or passing 10 through hopper or gatherer 34,--34., I wish to claim broadly as it forms a means, to get the screening away from two parallel screens. In the drawing Fig. 6, 5^a. is a relief opening in the elevator, and grain emanating 15 from it slides back into the receiving hopper, it is not only a relief to the elevator in keeping it from clogging and jamming with grain, but it has great functional proclivities for assisting in the mixing of the units 20 even conditions of mixed grain.

Having thus described my invention I claim—

1. In a machine of the character described the combination of a feeding device and superimposed inclined shaking hurdles below 25 said feeding device an inclined shaking shoe below and receiving from said hurdles and comprising upper and lower screens of a different mesh, with an adjustable catch 30 board between the lower two screens and separate conveying receptacles receiving from each of said screens and from said catch board substantially as and for the purposes set forth.

2. In a device of the character described, the combination of superimposed inclined shaking hurdles, an inclined shaking shoe below and receiving from said hurdles and comprising upper and lower screens of a different mesh with an adjustable catch 40 board between the lower two screens substantially as and for the purpose set forth.

3. In a device of the character described the combination of superimposed inclined shaking hurdles an inclined shaking shoe below and receiving from said hurdles and comprising upper and lower screens of different mesh each of said lower screens being 45 adjustable in the direction of its length and an adjustable catch board intermediate said screens substantially as and for the purpose set forth.

4. In a device of the character described the combination of superimposed inclined shaking hurdles an inclined shaking shoe below and receiving from said hurdles, comprising upper and lower screens of a different mesh, each of said lower screens being 55 adjustable in the direction of its length, an adjustable catch board intermediate said screens and separate conveying receptacles from each of said screens and from said catch board substantially as and for the purpose set forth.

5. In a device of the character described

the combination of superimposed and inclined shaking hurdles, an inclined shaking shoe below and receiving from said hurdles, a hood over said hurdles, and an adjustable curtain at the discharge end of said inclined 70 hurdles, that may be raised or lowered, when necessary to regulate the air currents that emanate from the fan; substantially as and for the purpose set forth.

6. A hurdle comprising a series of superimposed inclined parallel shaking screens, each screen being supported at its ends by imperforate shelf members, the shelves at the upper ends of the screens, alternating in width from narrow to broad downward 80 through the series, substantially as and for the purpose set forth.

7. A hurdle comprising a series of superimposed inclined parallel shaking screens each screen being supported at its ends by 85 imperforate shelf members, the shelves at the upper ends of the screens, alternating in width downward from narrow to broad and broad to narrow to broad as shown, substantially and for the purpose set forth.

8. In a machine of the character described, in combination, a receiving hopper, an elevator, a distributing conveyer, a feeding device, superimposed inclined shaking hurdles, a relief spout, a return conveyer and 95 a secondary hopper all constructed and arranged in such manner that grain placed in the receiving hopper is elevated to the distributing conveyer, and delivered to the feeding device the surplus passing on and 100 descending the relief spout to the return conveyer which carries it with overflows from the shaking hurdles to the secondary hopper which feeds it back into the elevator preceding grain in the receiving hopper.

9. In a machine of the character described the combination of a feeding device and superimposed inclined shaking hurdles an inclined shaking shoe below and receiving from said hurdles and comprising upper and lower screens with an adjustable catch board between the lower two screens of the lower shoe and separate conveying receptacles from each of said screens, and a lower receptacle to receive from the catch 110 board and from under the lower screen, substantially as shown and for the purpose set forth.

10. In a machine for separating uneven mixtures of mixed grain, a separating device, a distributing device capable of delivering a surplus of grain to insure a flooding of the separating device, means for returning the surplus grain and grain from the separating device to the distributing device, 120 together with a sufficient supply of additional grain, whereby a supply of grain is maintained in the machine and the feed to the separating device is equalized.

11. In a grain separating and cleaning 130

machine, separating and cleaning devices, means for equalizing the conditions of mixed grain, consisting of means for returning to the separating and cleaning devices, part of the grain which has been treated by them, in association with but ahead of a fresh equalizing supply of grain.

In testimony whereof I have hereunto set my hand and seal this 25th day of March, 1918.

JOHN LUCAS.

In presence of—

IRENE McCARTY,
CHAS. P. McALMOND.
